RECEPTACLE FOR THREADED NEEDLES

Charles R. Yingling, Baltimore, Md.

Application May 11, 1949, Serial No. 92,669

4 Claims. (Cl. 223—109)

1

This invention relates to receptacles and packages, and especially to a receptacle for threaded needles, though also useful for receiving unthreaded needles, pins, etc.

One object of this invention is to provide a compact kit for use by members of art-schools, art-clubs or societies where various kinds, sizes and colors of thread are necessary to effect color schemes, and where it is expeditious and otherwise advantageous to have the different kinds, sizes and colors displayed side by side for ready comparison and selection by the user.

Another object is to provide this device with such arrangement of elements that enables the respective needles to help keep the respective threads stretched around and between any elected number of the pins and hitch-elements which contribute to preventing the threads from tangling or interfering with one another.

Another object is to provide this device with all its elements in a unitary, compact and convenient arrangement that can be carried in a pocket, purse or hand-bag with a large number of threaded and unthreaded needles attached in readiness to be detached and used without loss of time for threading at the time of starting to work therewith.

Other objects and important features are pointed out or implied in the following details of description, in connection with the accompanying drawings in which:

Figure 1 is a top plan view of a simple form of the invention that has a part of the upper plate broken away and removed with some of the elements or features like those shown at 4, 5, and 6, to disclose some of the parts 7 and 9 on the lower plate 8; also showing (in dot-dash lines) the shape of the needle-cushion that normally fits in one of the spaces 10.

Figure 2 is a sectional view taken along the line 2—2 of Fig. 1.

Figure 3 is a top-plan view of a modified form of the invention containing a few needles with their respective threads *t* wound in different ways on and stretched between their respective elected groups of pins 5; a portion of the cover or casing 11 being broken away and in section at the lower left, showing a part of the upper plate 2a.

Figure 4 is a side elevation of the device shown in Fig. 3; a portion at left end of the casing 11 being broken away and in section to show parts of the surfaces 3a of the upper plate, 9a of one of the spacing blocks, and 8a of the lower plate; also showing a thread *t* attached to a needle-end at *n*, and wound and stretched around two hitch-elements 6a near the thread-end-portions.

Figure 5 is an elevational view of the device in Figs. 3 and 4, showing a needle-end *n* engaged with a thread *t* that is wound around and

2

stretched between pins 5 and hitched to a hitch-element 6.

Referring to these drawings in detail, in which similar reference numerals refer to different parts in the several views, the invention is described in detail as follows:

In a broad and generic sense, the invention is a special receptacle for threaded needles, and includes a plate 1 or 1a, having upper surfaces 2 or 2a and a relatively narrow peripheral surface 3 or 3a, and having needle-receiving channels 4 or 4a extending thru said narrow peripheral surface and transversely of said wide surface; a plurality of pins 5 being united with said plate and projecting outward from opposite marginal portions of said wide surface and being adapted to have a thread *t* wound around and stretched between them while the thread extends thru a needle *n* that is within one of said needle-receiving channels; and the invention also includes a plurality of thread-hitching clamp-elements 6 or 6a that are united with said plate and extending outward therefrom at points spaced from said pins and adapted to clamp and hold end-portions of a thread *t* when the latter is wound around an elected number of said pins 5.

The invention also includes a needle-receiving cushion 7 or 7a secured to said plate and having its points of needle-entrance substantially at said peripheral narrow surface 3 or 3a.

A plate 8 or 8a is secured to the opposite side of the first said plate from said wide side thereof by means that include spacer blocks 9 or 9a. Each spacer-block 9a is cross-notched at 9n; and the ends of the casing 11 have openings 11o (see Fig. 5) that register respectively with notches or channels 9n, so needles can be pushed through these openings and into the cushion 7a; and if said needles be threaded, the thread can be extended to adjacent pins 5, wound therearound, stretched therebetween, and have their end portions pressed into and clamped by the hitch-elements or clamps 6. The clamping is effected by the thread being pushed or pulled into the acute angle-space around the elected hitch-element 6.

When the user is ready to sew with any elected kind or color of thread and attached needle she (or he) grasps the free end of that thread, pulls it out from its clamped engagement with the hitch-element 6 or 6a, then disengages it from the pins 5, and uses it to pull the engaged needle from the cushion 7a or 7c or from any channel 4 or 4a that has no cushion therein. The channels 4 are shown as bores, but the channels 4a are shown as if cut by saws, and as the casing 11 closes the primarily open top of each channel, and as the openings 11o are narrower than the channels 4a, the cushions 7c that fill the channels 4a cannot come out from these channels.

In full lines and in dotted lines, in Fig. 1, the positions of four spacing blocks 9 are shown between the upper plate 1 and the lower plate 8, and glue or other appropriate means may be employed for securing these spacing blocks to the upper and lower plates; and although only one space 10 is indicated between two adjacent blocks 9, it may be readily understood that there are four of such spaces, and that they are normally filled with cushion 7 of fibrous or other appropriate material, although one of said cushions 7 is omitted at the lower right of Fig. 1, while its shape is indicated in dot-dash lines in a position slightly removed outward from its normal position such as indicated at the upper-right in Fig. 1, where they can be secured by glue or other appropriate means.

Though cushions are shown in the bores or channels 4 of Figs. 1 and 2, because they are not absolutely essential, it is preferable to provide them with cushions which may be treated with paraffin or other appropriate material for lubricating the needles and preventing them from becoming rusted or rough. For the purposes just mentioned, cushions 7c are provided in the respective channels 4a in Fig. 4, and access can be had to these cushions through openings 11o in the outer covering or casing 11 for inserting and withdrawing needles. When threaded needles are in any of the cushions 7, 7a, or 7c, their respective threads can be wound around and stretched between any selected groups or arrangements of the pins 5 that are most convenient thereto; and the end portions of the respective threads can be wound or pressed into any one or two of the hitch-devices or thread-clamps 6, in Figs. 1 to 5 inclusive; and in the modified form in Figs. 3, 4 and 5 the elements or parts 1a, 2a, 3a, 4a, 7a, 9a and 10a have functions corresponding respectively to the elements or parts 1, 2, 3, 4, 7, 8, 9 and 10 of the similar parts in Figs. 1 and 2.

In Figs. 3, 4 and 5, the thin cover or casing 11 is shown; and though no such casing is provided in Figs. 1 and 2, it is within the scope of this invention to provide the same. The casing 11 is secured on the surface 2a, 3a and on the elements 8a and 9a by glue or other appropriate means (not shown); and it has openings at 4a and at 10a for access to the cushions 7a and 7b respectively.

The hitch-elements 6 are shown as composed respectively of two-concavo-convex discs which are centrally apertured and held together by means of pins which may be similar to the pins 5 and which extend through the upper plate 1 in Figs. 1 and 2 and through the casing 11 and upper plate of which a portion 3a is shown in Fig. 4, and another portion 2a is shown in Fig. 3. Several of these pins are indicated at 6p in Figs. 2 and 5.

The thread-holding and hitching devices 6a are shown in the form of tacks having large heads with the convex side against the cover or casing 11, the shanks thereof being indicated by the dotted lines in Fig. 3. Inasmuch as these hitch devices 6 and 6a may be of construction other than shown and described, they are not described more specifically and are not claimed per se.

This invention is not limited to the precise construction and arrangement as herein described and as shown in the drawings, for the invention is susceptible of numerous changes within the scope of the inventive ideas as implied and claimed.

My invention is claimed as follows:

1. In a special receptacle for threaded needles, 75

the combination of a plate having a relatively wide surface and a relatively narrow peripheral surface and having needle-receiving channels extending through said narrow surface and transversely of said wide surface, a plurality of pins united with said plate and projecting outward in sets near the peripheral edge portions and substantially central portions of said wide surface and adapted to have a thread wound around and stretched between any two pins of said sets while said thread extends through a needle that is within one of said needle-receiving channels, and a plurality of thread-hitching clamp-elements united with said plate and extending outward from said wide surface at points spaced from said pins and adapted to clamp and hold end-portions of a thread when the latter is wound around an elected number of said pins.

2. In a special receptacle for threaded needles, 20 the combination of a plate having a relatively wide surface and a relatively narrow peripheral surface, a needle-receiving cushion, a plurality of pins united with said plate and extending outward from opposite edge-portions of said wide surface and adapted to have a thread wound around and stretched between them while said thread extends through a needle that is within said needle-receiving cushion, a plurality of thread-hitching clamp-elements united with said 25 plate and extending outward from said wide surface at points spaced from said pins and adapted to clamp and hold end-portions of a thread when the thread is wound around an elected number of said pins, said needle-receiving cushion being secured to said plate and having its points of 30 needle-entrance substantially at said peripheral narrow surface.

3. In a special receptacle for threaded needles, 40 the combination of two plates each having relatively wide surfaces and having relatively narrow surfaces substantially at right angles to said wide surfaces, said plates being spaced from one another throughout the greater portion of adjacent wide surfaces thereof, a needle-receiving cushion 45 secured in the space between said adjacent wide surfaces, and two complementary rows of thread-receiving and thread-clamping elements united with said plates and projecting outward therefrom and adapted to have thread wound around a number of them while said thread extends 50 through a needle that is within said cushion, each of said thread-clamping elements being effective to clamp and hold end-portions of said thread against accidental detachment therefrom.

4. The structure defined by claim 3 in combination with a row of pins united with and extending out from one of said narrow surfaces in a convenient relation to have a portion of a thread wound around a group composed of a number of said pins and a number of said thread-clamping elements while a part of said thread is extended through a needle that is within said needle-receiving cushion.

CHARLES R. YINGLING.
